PROCESS FOR DEWAXING PETROLEUM OIL

Hans Svano, Fairville, Pa., assignor to E. I.
du Pont de Nemours & Company, Wilmington,
Del., a corporation of Delaware

Application August 24, 1931, Serial No. 559,025

11 Claims. (Cl. 196—19)

This invention relates to a process for the dewaxing of oils and particularly to the separation of mineral wax, such as paraffin, from a petroleum oil containing the same by chilling in the presence of a solvent.

In refining lubrication oil the crude is generally distilled to remove the lighter fractions. This treatment results in a concentration of the paraffin wax in the residual heavy oils. A number of methods are employed for separating the wax from the oil, the nature of the process being governed by the grade of oil it is desired to produce. For example, if a medium pour test machine oil is to be prepared, the concentrate may be diluted with naphtha, say 3 parts of naphtha to 1 part of oil, and the resulting mixture chilled to a few degrees below 0° F., at which temperature a portion of the wax crystallizes out and is filtered and/or centrifuged from the oil. Owing to the solubility of the wax in the naphtha at this temperature, much remains in the finished oil. To obtain a zero pour test oil, the naphtha-oil mixture must be chilled to very low temperatures, such as, for example, —50 to —60° F. or lower, an operation which is very expensive. The oil must also be very slowly cooled, due to the fact that rapid cooling of a naphtha-oil mixture separates a wax difficult and often impossible of separation from the mixture.

The great disadvantage inherent in the use of naphtha per se as a dewaxing agent is due to its high relative solubility of the wax even at very low temperatures. To obtain by its use alone, therefore, a high-grade, wax-free oil is a very expensive operation.

An object of the present invention is to provide an improved process for the dewaxing of lubricating oils. Another object of the invention is to provide a wax-immiscible solvent for the dewaxing of lubricating oils whereby high-grade lubricants can be produced. Other objects and advantages will hereinafter appear.

I have found that high-grade, substantially wax-free, lubricating oils can be prepared from wax-bearing heavy oils by employing in conjunction with naphtha a water-insoluble aliphatic alcohol with or without an organic liquid which is soluble in the alcohol but substantially insoluble in mineral oil. By dewaxing with my dewaxing agents and by the process as will hereinafter be more fully described, high-grade oils can be obtained by chilling to but medium low temperatures; while if naphtha were the sole dewaxing agent, a lubricant containing a large amount of wax would be obtained under the same conditions.

I have made the surprising discovery that when naphtha is mixed with a water-insoluble aliphatic alcohol in amounts ranging preferably from 20 to 80% naphtha, the solubility of the solution for the mineral oil wax is so markedly decreased that high-grade lubricating oils can be obtained from crudes, having high wax content, by chilling the crude oil-naphtha-alcohol mixture to temperature but slightly below 0° F. Without the presence of these alcohols, a considerably lower temperature is required to give as good a dewaxing.

Furthermore, I have found that the solubility of the naphtha for the mineral wax can be still further decreased by having present an organic liquid wax precipitating agent, such as methanol, ethanol, acetone, etc., in amounts up to approximately 10% of the solvent mixture employed. More should not be employed for reasons which will presently be apparent. By the employment of my dewaxing agent, comprising naphtha, a water-soluble and a water-insoluble organic liquid, lubricating oils of superior quality can be prepared at an extremely low cost.

I have developed a still further advantage which when utilized in my preferred dewaxing process, renders the separation of the solvents from the dewaxed oil more economical than the simple distillation processes which would ordinarily be used. This process may be more readily comprehended by reference to the accompanying flow sheet divisions of which will hereinafter be referred to by numbers, and the following description of my preferred dewaxing process which is descriptive of one manner of carrying out my invention, but which will not limit in any way the scope thereof.

Undewaxed lubricating oil, such as "residual unfiltered cylinder stock" (1) is diluted (2) with my preferred dewaxing agent to give a mixture containing 70 parts by volume of the dewaxing agent to 30 parts by volume of the oil. The resulting very fluid mixture is filtered through fuller's earth and then chilled (3) as rapidly as desired to approximately 32° F. or lower, depending upon the grade of lubricating oil being made. The precipitated wax is separated (4) from the oil-dewaxing agent mixture by filtration, gravity and/or centrifugal means. The dewaxing agent may be separated from the oil in any suitable manner, such as by distillation, extraction, etc., but I prefer to separate it by the following novel process.

An alcohol-miscible but oil-immiscible liquid, such as methanol, ethanol, acetone, or mixtures

thereof, or a liquid having like qualities, is added (6), as an extracting liquid, to the mineral oil-dewaxing agent mixture until two layers separate. This will generally be effected, for example, when approximately 15% methanol has been added; on the other hand, 30% ethanol and 16% acetone are generally required to effect the desired separation. (The percentage is calculated as percentage by volume of the separating liquid to the total volume of mineral oil+dewaxing agent.) It is to be understood that the percentage may vary 5 to 10% either way, and in some cases more according to the type of oil-dewaxing agent mixture being treated. By adding methanol, an oil layer will separate (7) containing the major part of the original oil which can readily be decanted and washed with methanol (8) to recover the small amount of dewaxing agent contained therein, the methanol washings (15) being subsequently used with fresh extracting liquid. The last traces of the solvent may be, if thought necessary, stripped from the dewaxed lubricating oil by distillation (9). The thus purified and dewaxed oil may now be sent to storage (10).

The solvent layer may, if desired, be distilled (12) to remove the excess of the extracting liquid. Complete removal of the extracting liquid is not necessary, as will be more fully explained hereinafter. The extracting liquid condensate (13) may be employed for washing the dewaxing agent from the dewaxed oil layer and the dewaxing agent residue (14) used in the next batch of oil to be treated.

My dewaxing agent should contain such a proportion of naphtha and alcohol, or other suitable solvents, and be added to the crude oil in such amounts, that the desired dewaxing is effected at the highest temperature possible and the fluidity of the oil-dewaxing agent mixture at the precipitation temperature, i. e. the temperature at which the desired amount of wax has been separated, should be such that rapid and efficient filtering and/or centrifuging operations may be effected. I have found that no optimum proportion can be given which will be satisfactory for all types of crude. It may be stated generally, however, than an oil to dewaxing agent ratio of from 1 to 1.5 to 1 to 5, with the mean ratio of 1 to 3 as usually most satisfactory, will give good results. My dewaxing agent may contain no naphtha but comprise only one or more water-insoluble alcohols, with or without an oil-immiscible organic liquid. As such a dewaxing agent is, under some conditions, not always sufficiently fluid, I generally prefer to also have naphtha or like hydrocarbons present.

The percentage of naphtha in the naphtha alcohol dewaxing agent, may vary from approximately 20 to 80%, and when a wax precipitating agent is present the latter may constitute up to approximately 10% of the composition of the dewaxing agent. I have found it to be of advantage to use as the extracting liquid the same liquid that is present in the dewaxing agent as a wax precipitating agent. Methanol, ethanol, acetone and liquids which are substantially oil-immiscible and in which the wax is insoluble are well suited for this purpose. Their presence with the dewaxing agent tends to decrease the solubility of wax in that agent, particularly at low temperatures. It is not necessary, therefore, to completely separate the extracting liquid from the dewaxing agent, after the latter's decanta-

tion from the oil, as up to 10% may be left with the dewaxing agent.

The water-insoluble aliphatic alcohols which I prefer to use are those containing seven or more carbon atoms and particularly mixtures of such alcohols. A mixture of alcohols of this nature which is particularly well-fitted for this work is the higher fraction of oxygenated organic compounds resulting from the catalytic hydrogenation of the oxides of carbon under pressure. In the organic synthesis described in the copending application of Roger Williams, Serial No. 185,339, a method of synthesizing such compounds is described. The organic compounds synthesized by this process cover a boiling range up to approximately 410° F. and include such alcohols as methyl, ethyl, propyl, butyl, amyl, hexyl, etc., the alcohols above ethyl having both straight and side-chain groupings. The fraction of this mixture which I prefer to use either alone or together with naphtha and/or an alcohol-miscible and oil-immiscible liquid, boils from approximately 290° F. up to approximately 410° F. and is substantially water insoluble.

The wax (5) separated by filtration or centrifugal means will contain, of course, some oil and dewaxing agent. I remove the oil by washing with the dewaxing agent, using the resulting oil-containing dewaxing agent, without separation of the oil, for subsequent dewaxing treatment of the crude. The dewaxing agent remaining in the wax may be removed by simple evaporation.

As indicated in the above general process, I prefer to add the naphtha and/or water-insoluble alcohols prior to the filtration of the crude. In some instances, however, it may be advantageous to first thin the crude with naphtha or other thinning agent and after filtration and prior to wax removal, add the required amount of the water-insoluble alcohol.

There are numerous other substances which may be used in lieu of naphtha such, for example, as ethylene chloride, benzol, butyl formate, etc. Any liquid which will give, at the temperature of precipitation of the wax, sufficient fluidity to the mixture, and preferably one in which the wax is substantially insoluble at that temperature, may be considered an equivalent thereof.

Various changes may be made in the process for dewaxing oils, or in the dewaxing agents or extracting liquids employed, without departing from this invention or sacrificing any of the advantages that may be derived therefrom.

I claim:

1. In a process of separating wax from a wax-bearing oil, the steps which comprise diluting the oil with a dewaxing agent containing a mixture of water-insoluble alcohols boiling between approximately 290° F. and approximately 410° F. and obtained by the catalytic hydrogenation of carbon oxides under high pressure, chilling the resulting mixture to a temperature of 32° F. or lower, separating the precipitated wax from the oil and dewaxing agent, and recovering the dewaxing agent from the oil and wax.

2. In a process of separating wax from a wax-bearing oil, the steps which comprise diluting the oil with a dewaxing agent containing a mixture of water-insoluble alcohols boiling between approximately 290° F. and approximately 410° F. and obtained by the catalytic hydrogenation of carbon oxides under high pressure, and an alcohol-miscible and substantially oil-immiscible precipitating agent, chilling the resulting mixture in order to precipitate the wax, separating the pre-

cipitated wax from the oil and dewaxing agent, and recovering the dewaxing agent from the oil and wax.

3. In a process of separating wax from a wax-bearing oil, the steps which comprise diluting the oil with a dewaxing agent containing naphtha and a mixture of water-insoluble alcohols, boiling between approximately 290° F. and approximately 410° F. and obtained by the catalytic hydro- 10 genation of carbon oxides under high pressure, chilling the resulting mixture to a temperature of 32° F. or lower, separating the precipitated wax from the oil and dewaxing agent, and recovering the dewaxing agent from the oil and wax.

15 4. In a process of separating wax from a wax-bearing oil, the steps which comprise diluting the oil with a dewaxing agent containing a mixture of water-insoluble alcohols, boiling between approximately 290° F. and approximately 410° F. and 20 obtained by the catalytic hydrogenation of carbon oxides under high pressure, and naphtha mixture containing 20-80% naphtha, chilling the resulting mixture to a temperature of 32° F. or lower, separating the precipitated wax from the oil 25 and dewaxing agent, and recovering the dewaxing agent from the oil and wax.

5. In a process of separating wax from a wax-bearing oil, the steps which comprise diluting the oil with a dewaxing agent containing a mixture 30 of alcohols having a boiling range from approximately 290° F. to approximately 410° F., said alcohols having been obtained by the catalytic hydro- 35 genation of a carbon oxide under high pressure, chilling the resulting mixture in order to precipitate the wax, separating the precipitated wax from the oil and dewaxing agent, and recovering the dewaxing agent from the oil and wax.

40 6. In a process according to claim 1, after separating the precipitated wax, adding to the de- 45 waxed oil an organic liquid which is soluble in the alcohol but substantially insoluble in the oil, whereby the oil and dewaxing agent separate in

two layers, and separating the oil layer from the layer containing the dewaxing agent.

7. In a process according to claim 1, after separating the precipitated wax, adding to the de- 80 waxed oil an alcohol having less than four carbon atoms, whereby the oil and dewaxing agent separate in two layers, and separating the oil layer from the layer containing the dewaxing agent.

8. In a process according to claim 1, after separating the precipitated wax, adding to the de- 85 waxed oil methanol, whereby the oil and dewaxing agent separate in two layers, and separating the oil layer from the layer containing the dewaxing agent.

9. In a process according to claim 2, after separating the precipitated wax, adding to the de- 90 waxed oil an organic liquid which is soluble in the alcohol but substantially insoluble in the oil, whereby the oil and dewaxing agent separate in two layers, and separating the oil layer from the 95 layer containing the dewaxing agent.

10. In a process of separating wax from a wax-bearing oil, the steps which comprise diluting the oil with a dewaxing agent consisting of a mixture of oxygenated organic compounds boiling 100 between approximately 290° F. and approximately 410° F. and obtained from the catalytic hydro- 105 genation of carbon oxides under elevated temperatures and pressures, filtering the resulting mixture to precipitate the wax, and after separating the wax from the oil-dewaxing agent mixture, adding a given quantity of methanol to the mixture sufficient to separate the oil from the dewaxing agent and methanol.

11. In a process of separating the constituents 110 of a mixture containing an oil and a mixture of alcohols having a boiling range from approximately 290° F. to approximately 410° F., said alcohols having been obtained by the catalytic hydro- 115 genation of a carbon oxide under high pressure, which comprises adding methanol to the mixture.
